DESIGN FOR A HANDBAG

Rene Courtine, New York, N. Y.

Application April 6, 1939, Serial No. 84,080

Term of patent 3½ years

To all whom it may concern:

Be it known that I, Rene Courtine, a citizen of the United States and resident of New York city, in the county of New York and State of New York, have invented a new, original, and ornamental Design for Handbags, of which the following is a specification, reference being had to the accompanying drawing, forming a part thereof.

Fig. 1 is a perspective view of a handbag, showing my new design in open position.

Fig. 2 is another perspective view of the same in closed position.

Fig. 3 is a top plan view of the same.

I claim:

The ornamental design for a handbag, as shown.

RENE COURTINE.
